[57] CLAIM

The ornamental design for a fowl roaster rack, as shown and described.

DESCRIPTION

FIG. 1 is a front perspective view of a fowl roaster rack, showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a top plan view thereof;

FIG. 8 is a front perspective view showing a modified form of FIG. 1 with the clamping bolts and nuts in inverted position;

FIG. 9 is a front elevational view thereof;

FIG. 10 is a right side elevational view thereof;

FIG. 11 is a rear elevational view thereof;

FIG. 12 is a left side elevational view thereof;

FIG. 13 is a bottom plan view thereof; and

FIG. 14 is a top plan view thereof.

The broken lines in FIGS. 1-5 and 8-12 represent a fowl skewered in roasting position and the broken lines in FIGS. 7 and 14 represent fragments of four rods of a roasting oven grill to which the two clamping plates are secured. The broken lines are for informational purposes only and form no part of the design.
